MEASURING AND CUTTING MACHINE

Harry S. Rubens, Chicago, Ill.

Application June 21, 1933, Serial No. 676,915

18 Claims. (Cl. 164—42)

This invention relates to a measuring and cutting machine and more particularly to a machine for measuring and cutting a continuous web of material into strips or sheets of equal length.

5 While the invention is especially suitable for measuring and cutting into sheets of equal size a continuous web of cellulose wrapping material such as "Cellophane" wound upon a roll and drawn therefrom and fed through the machine 10 by feed mechanism which operates to feed the web intermittently or step by step and in equal lengths, it is to be understood that the invention may be employed with paper or other materials as suitable or desired.

15 In the specific embodiments selected for illustration, the invention has certain advantages not found in machines of the prior art, first of which is its ability to handle very thin and flexible cellulose and like materials which have advantages 20 well known in the art and have come into wide use for wrapping purposes and the like. The machine which I provide is compact and inexpensive and operates positively and effectively. It is light in weight and easy to manufacture and 25 assemble, and the parts are all such as to be formed at minimum cost, simple operations on relatively few and small parts only being required. The feed rolls of the mechanism for drawing the material from the roll and feeding 30 it through the machine are both preferably positively driven, and the means for operating the feed mechanism has stop means for limiting positively the feed mechanism actuating operation, and preferably also the resetting movement of 35 the feed mechanism operating means. The stop means for limiting the feed mechanism actuating operation is preferably adjustable for the purpose of adjusting the lengths of the strips or sheets measured and cut by the machine, and 40 the stop means for limiting the resetting movement of the feed mechanism operating means may be and, in the illustrated embodiments, is adjustable to assure proper positioning of the feed mechanism operating means in the resetting 45 movement thereof.

I further wish to call attention to the fact that the mounting and replacement of the rolls of material which are measured and cut by the machine are obtained with ease and facility; that 50 at least one of the feed rolls is preferably held yieldingly in cooperating with the other feed roll by means which assumes proper feeding cooperation of the surfaces of these rolls at all times; and that provision is made for holding and guiding 55 the swingable arm,

Another feature which is of importance in my invention resides in the provision of guide means for guiding the material from the feed mechanism, which guide means is adjustable for sheets of different widths.

Another feature is the provision of means for preventing back-lash in the feed mechanism.

Another feature is the provision of means for yieldingly preventing over-running or turning of the roll of material too freely on its rotatable support.

Further features and advantages will be apparent from the following detailed description taken in connection with the accompanying drawings, in which:

Figure 1 is a fragmentary side view of a machine embodying the present invention;

Figure 2 is a fragmentary top plan view;

Figure 3 is a fragmentary vertical section taken on the line 3—3 of Figure 2;

Figure 4 is a fragmentary detail view showing a modified form of means for holding the peripherally toothed feed mechanism operating wheel against back-lash;

Figure 5 is a fragmentary side view of the another embodiment of the invention; and

Figure 6 is a fragmentary perspective view showing a brake device for preventing back-lash in the feed mechanism.

Referring to the drawings, the machine shown 30 comprises a bench, table, or other member, having a flat horizontal top 5. Secured fast at 6 to the top 5 are a pair of uprights or frame members 7, the upper ends of which are notched at 8 to receive the opposite ends of the shaft or trunnions 35 9 of the roll of material 10.

The material 10 is preferably a thin flexible web of cellulose material such as "Cellophane" wound upon the roll, but it is to be understood that any other suitable or preferred material, such 40 as paper or the like, may be employed within the scope of the present invention. The instant machine is especially suitable for measuring and cutting sheets of wrapping material for use with the wrapping method covered by my copending 45 application Serial No. 676,420, filed June 19, 1933. It is not, however, in anywise limited to such use, but may be employed wherever it is desired to measure and cut a continuous web of material into strips or sheets of equal lengths.

Mounted in one of the uprights 7 beneath the trunnions 9 and with its axis in a vertical plane through the axis of the trunnions 9 is a short shaft 12 which, in the embodiment of Figures 1 to 3 inclusive, is fixed against rotation in the adja- 50 55

cent upright and projects outwardly therefrom. A relatively large spur gear or other peripherally toothed wheel 13 is mounted upon the shaft 12 for rotation freely upon the shaft 12 in a clockwise direction, and preferably is held at all times against back-lash or turning movement in a counterclockwise direction (Figure 1) by an over-running clutch indicated at 14.

Other suitable or preferred means may, of course, be provided for holding the spur gear or peripherally toothed wheel against back-lash or rotation in a counterclockwise direction in lieu of the over-running clutch 14. For example, in the modification shown fragmentarily in Figure 4, the relatively large spur gear or peripherally toothed wheel indicated at 13' and which corresponds with the gear or wheel 13 of Figures 1 to 3 inclusive, is held against back-lash or rotation in a counterclockwise direction by a locking dog 16 pivoted at 17 upon the adjacent upright 7 which, in this case, is extended above the periphery of the wheel or gear 13'. The wheel 13', in this embodiment, is either rotatable loosely upon the short shaft 12' which is then fixed against rotation in the adjacent upright, or it may be fixed upon the shaft 12', in which case this shaft 12' is rotatable freely in a suitable bearing on the upright. The nose of the dog 16 is pressed yieldingly at all times into engagement with the teeth in the periphery of the wheel or gear 13' by a spring 18 and operates to permit turning of the wheel in a clockwise direction and at the same time to hold the same against back-lash or turning in a counterclockwise direction.

Now, referring again to Figures 1 to 3 inclusive, an arm 20 is mounted substantially intermediate its length upon the shaft 12 to swing freely in clockwise and counterclockwise directions. To turn the gear or wheel 13 in a clockwise direction by clockwise swinging movement of the arm 20 about the shaft 12, an actuating dog 21 is pivoted to the arm 20 at 22. The nose of the dog 21 is pressed yieldingly at all times into engagement with the teeth in the periphery of the wheel or gear 13 by a spring 23 connected at one end to the arm 20 at 24, and at the opposite end to the tail of the dog 21 at 25. The dog 21 operates to turn the wheel 13 positively in a clockwise direction with clockwise swinging movement of the arm 20, and at the same time yieldingly over-runs the teeth of the wheel 13 in the opposite direction to permit return or resetting movement of the arm 20 free of the wheel 13 and without turning the same in a counterclockwise direction.

The mechanism for drawing the web 28 of material from the roll 10 and feeding it through the machine comprises a pair of feed rolls 29 and 30. These rolls are preferably of hollow cylindrical or drum-like form as shown in Figure 3, and their cylindrical outer surfaces are preferably surfaced or covered with rubber or like material at 31 and 32 respectively. The roll 29 has fixed thereto at its opposite ends trunnions 34 positioned beneath the wheel 13 and mounted or journaled rotatably in the opposite uprights 7 with their axes in the vertical plane of the axes of the roll 10 and wheel 13. The trunnion 34 at the side of the machine at which the wheel 13 is disposed projects outwardly from the adjacent upright 7 and has fixed thereon a pinion 35 which meshes constantly with the teeth in the periphery of the gear wheel 13. The trunnions 36 fixed to the lower roll 30 are loosely journaled at 37 in the upright 7, the journaling openings provided for

the trunnions 36 in the upright 7 being elongated slightly as shown in Figure 1 to permit the roll 30 to yield slightly with respect to the roll 29 for assuring proper feeding cooperation of the surfaces of these rolls at all times. The roll 30 is pressed yieldingly against the roll 29 by coiled springs 39 confined in sockets 40 in enlargements on the webs 41 integral with the uprights 7 and between screws 42 and stud-like projections 43 integral with the trunnions 36, and which operate slidingly in the sockets 40. Threading of the screws 42 into or out of the sockets 40 adjusts the tension of the springs 39, it being understood that there is one of such spring arrangements at each of the opposite ends of the roll 30 although only one such arrangement is shown in the drawings.

The trunnions 34 and 36 at the side of the machine opposite the side at which the wheel 13 is disposed project outwardly from the adjacent uprights 7 and have fixed thereon meshing spur gears 45 and 46, which gears are of equal diameter and drive the roll 30 positively in a clockwise direction by turning movement of the roll 29 in a counterclockwise direction and at a one-to-one ratio with the roll 29.

The uprights 7 have integral lateral legs 48 seating or secured at 49 to the top 5. These legs carry the horizontal plate 50 upon which the web 28 is fed from the machine. The plate 50 is mounted upon the horizontal part 51 of a web connecting the opposite legs 7 and the cutting or knife mechanism, designated generally at 52 and to be described presently, is mounted upon the vertical leg 53 of this connecting web. The under side of the inner end of the plate 50 is tapered at 54 to fit well between the rolls 29 and 30, and the legs 48 may be webbed at 55, the web 55 on the leg 48 at the side at which the wheel 13 is disposed having an opening 56 in the plane of swinging movement of the arm 20.

The right-hand end of the arm 20 (Figure 1) is depressed or actuated by a treadle 60. The treadle 60 is hinged or pivoted at 61, as for example, upon a bracket on the floor, to swing vertically, and its opposite end is connected by a chain 62 and rod 63, or other suitable connecting elements, to the arm 20. The lower end of the element 62 is connected at 64 to the free end of the treadle 60, and the upper end of the element 62 is connected to the lower end of the rod 63 at 65. The rod 63 is reciprocable vertically through an opening 68 in the top 5 and through the opening 56 in the web 55 of the adjacent frame or upright 7, and the upper end of the rod 63 has an eye 69 by means of which and a thumb nut 70 the upper end of the rod is pivoted to the adjacent end of the arm 20. Longitudinally aligned openings 72 in the arm 20 permit the upper end of the rod 63 to be pivotally connected to the arm at different positions inwardly and outwardly from the axis of swinging movement of the arm, or, in other words, these openings 72 permit adjustment of the pivotal connection between the arm 20 and the rod 63. Slidable upon the rod 63 above the lateral extensions 75 of the web 55 is a collar 76, which collar 76 is adapted to be secured fixedly in different positions upon the rod 63 by a set screw 77. The collar 76 constitutes an adjustable stop which, by engagement with the projection 75 of the web 55 in the downward movement of the rod 63, limits the downward movement of this rod and thereby the down stroke of the arm 20 swingably about its axis.

By loosening the set screw 77 and adjusting 75

the collar 76 to different positions upon the rod 63 and again tightening the screw 77 when the collar 76 is positioned as desired, the amount of downward swinging movement of the arm 20 upon each depression of the treadle 60 is adjusted. This adjusts the amount of rotation or turning movement imparted to the gear 13, and thereby the amount of turning movement imparted to the feed rolls 29 and 30 upon each actuation of the treadle 60. The amount of turning movement imparted to the feed rolls 29 and 30, in turn, determines the length of web fed through the machine upon each operation of the treadle and thereby the length of the sheets or strips 79 measured and cut by the machine.

At the opposite end of the arm 20 is a return or resetting mechanism therefor. This mechanism comprises a rod 80 vertically reciprocable through an opening 81 in the top 5 and provided at the upper end with an eye 82 pivoted to the arm 20 by means of a thumb screw or the like 83. A plurality of longitudinally aligned openings 84 in the arm 20 permit adjustment of the pivotal connection of the rod 80 to the arm 20 inwardly and outwardly from the axis of swinging movement of the arm. At the bottom of the opening 81 is an upwardly cupped or concave ring-like guide plate 85 through the opening in which the rod 80 passes. Mounted upon the rod 80 beneath the plate 85 for vertical sliding movement of the rod 80 therethrough is a collar 86, the top of which is rounded in conformity with the concave portion of the plate 85, and a spring 88 is coiled about the lower end of the rod 80 and confined between the bottom of the collar 86 and a collar 87 secured fast upon the lower end of the rod 80. As the treadle 60 is depressed, the outer end of the arm 20 is swung downwardly to drive the feed mechanism the predetermined amount, and the upward swinging movement of the inner end of the arm 20 draws the rod 80 up vertically through the opening 81. This upward movement of the rod 80 is against the tension of the spring 88 which is compressed thereby so that, after the feeding operation is completed and the treadle 60 released, the expansive effort of the spring 88 against the collar 87 will force the rod 80 downwardly and, through it, reset or return the arm 20 to position for the next feeding operation of the machine. As the spring 88 operates to reset or return the arm 20 to position for the succeeding operation the dog 21 rides freely over the peripheral teeth in the gear or wheel 13 and without turning this gear with this movement of the arm.

For the purpose of guiding the web 28 over the flat upper surface of the plate 50 as it is fed from the machine, the plate 50 is provided with a pair of side guides 90 and 91 spaced apart a distance substantially equal to the width of the web 28 and cooperating with the opposite edges of the web as shown in Figure 2 to guide the same from the machine. The guides 90 and 91 have entrance projections curved or spread outwardly at 92 and 93 to receive the web and guide the same between the parallel guide edges of the guides.

To permit adjustment of the space between the guides 90 and 91 for accommodating sheets or webs of different widths, the guide 90 is adjustably mounted upon the plate 50 for adjustment toward and away from the guide 91 which may be secured fast by screws 94. For purposes of this adjustment, the guide 90 has an integral lateral extension 95 provided with a slot 96 disposed at right angles to the width of the web 28, and a screw 97, the shank of which passes through

the slot 96, is adapted for securing the guide fast in any desired adjusted position. To prevent turning of the guide 90 about the shank of the screw 97, the outer end of the extension 95 engages and is guided in a notch 98 in the web 99 of the lateral leg part 48 of the adjacent frame part or upright 7 or, in lieu of this, a second screw (not shown) may be arranged outwardly of the screw 97 with its shank passing through the slot 96 and threaded into the adjacent frame or 10 upright part of the machine.

The cutting mechanism, designated in its entirety at 52, comprises a fixed cutting bar 100 secured to the vertical leg 53 of the web connecting the lateral legs 48 of the upright, as for example, by screws 101 and a swingable blade 102 pivoted loosely upon a bolt or screw 103 which passes loosely through lateral extensions 104 on the frame-work of the machine (Figure 2), and has threaded upon its opposite end a nut 105 and a lock nut 106. A washer 107 is disposed upon the shank of the bolt or screw 103 ahead of the nut 105, and a spring 108 is coiled about the shank of the screw or bolt and disposed between the washer 107 and the lateral frame extension 104. The knife 102 has a handle 110 and a cutting edge 112 which cooperates with the cutting edge of the bar 100. The part of the knife 102 along which the cutting edge 112 is formed say be normally disposed slightly obliquely with reference to the cutting edge of the bar 100, and as the blade or knife 102 is depressed the spring mounting at 108 permits the blade to swing laterally slightly into parallel cooperation with the cutting edge of the bar 100 as the blade is swung 35 downwardly into engagement with this bar. This assures proper cutting cooperation of the knife 102 with the bar 100 at all times, but the knife 102 may be of straight form and the cutting mechanism may be otherwise varied within the 40 scope of the present invention. The knife 102, in the illustrated embodiment, is operated manually by grasping the handle 110 and swinging the same downwardly into cooperation with the cutting edge of the bar 100, but it is to be understood 45 that this knife may be operated automatically from the foot treadle 60 or other feed mechanism operating means of the machine. The axis of the roll 30 is in a vertical plane through the axes of the roll 29, toothed wheel 13, and the 50 roll of material 10.

To prevent over-running or too free turning of the roll of material 10 on its rotatable support, one end of the journal for the roll has fixed thereon a collar or other suitable abutment 175. A 55 spring arm 176, secured fast at its lower end to a shaft 177, has an enlargement 178 at its upper end bearing against the adjacent end of the roll 10 and specifically against the hub or roll part proper. This spring 176 forces the collar 175, 60 at the opposite end of the roll, yieldingly against the adjacent upright 7, and holds the roll of material yieldingly against over-running or too free turning on its rotatable support. The shaft 177, which anchors the lower end of the spring arm 65 176, is slidable in a sleeved part 179 so that the spring arm may be moved toward and away from the upright at the opposite side of the machine to accommodate rolls of different lengths, and is secured fast in adjusted position by a set screw 70 180.

The operation of the illustrated embodiment of the invention is as follows:

The sheet or web of "Cellophane", paper or the like, is supplied and mounted in the machine 75

in roll form at 10, and the free end of the sheet or web 28 is led down and out between the feed rolls 29 and 30 over the plate 50 and between the guides 90 and 91. With the free end of the web positioned between the rolls 29 and 30, operation of the foot treadle 60 turns these rolls an amount determined by the position of the stop 76 to draw a predetermined length of web from the roll 10 and feed the same out between the guides 90 and 91. After depression of the treadle 60, the knife 102 is swung downwardly from its raised position shown in Figure 1 to cut the web 28 transversely across its width and thereby divide the sheet 79 therefrom. The depressions of the treadle 60 will feed equal lengths of the web 28 from the machine, and by operating the knife 102 after each web feeding actuation of the treadle 60 the web is cut into sheets or strips 79 of equal length. The operation of the web feeding means is intermittent and the cutter is operated after each operation of such web feeding means. As already pointed out, adjustment of the stop 76 on the rod 63 adjusts the length of the strips or sheets.

For the purpose of limiting positively the resetting movement or repositioning of the arm 20 after each actuation of the treadle 60, the rod 63 is provided with a second stop 120 adjustable thereon and fixed fast in such position by a set screw 121. The stop 120 operates beneath the lateral extension 75 of the adjacent upright and, by engagement with said lateral extension, limits the upward stroke of the rod 63 and thereby the resetting movement of the swingable arm 20. This stop assures proper positioning of the feed mechanism operating means in the resetting movement and the adjustability of this stop enables maintaining proper resetting positioning of the arm 20 so that this arm and the web feeding mechanism will operate properly upon each actuation of the treadle 60.

In the embodiment of Figure 5, the peripherally toothed wheel or gear member 125 corresponds with the peripherally toothed wheel or gear member 13 of Figure 1, and the arm 126, swingable about the axis of the shaft 127, corresponds with the arm 20 of Figure 1. In this embodiment, the arm 126, instead of having one feed mechanism actuating dog, has two such dogs 128, 129 pivoted at 130, 131 on opposite sides of the axis of swinging movement of the arm and having their noses pressed yieldingly into engagement with the teeth in the periphery of the wheel 125 by springs 132, 133. The roll of material is indicated at 134, the upper and lower feed rolls at 135 and 136 respectively, and the means for actuating the arm 126 is shown as comprising the vertically reciprocable rod 137, treadle 138, and connecting element 139. The top is indicated at 140 and the cutting mechanism is shown as comprising the fixed cutting bar 141 and swingable knife 142.

In this embodiment, the adjustable stop members 143 and 144 on the rod 137, for limiting the feed mechanism advancing movement and the return movement respectively of the arm 126, instead of cooperating with a lateral extension of a web part on one of the upright frame members of the machine, cooperates with a fixed stop indicated at 145. This stop 145 comprises a relatively short shaft or post secured fast at its inner end to the adjacent upright 146 and provided at its outer end with a square part 147, which square part has a transverse opening through which the rod 137 extends.

Instead of the resetting mechanism connected to the opposite end of the arm 126, as in Figure 1, the resetting or repositioning movement of the arm 126 is obtained by a coiled spring 149. This spring 149 is coiled about the shaft or trunnion 127 and has one end engaging the adjacent upright 146 and the opposite end 150 engaging the arm 126. As the outer end of the arm 126 is swung downwardly by the rod 137 this spring is tensioned, and when the treadle 138 is released it acts to return the arm 126 to position for the next operation, it being understood that in the clockwise swinging movement of the arm 126 the engagement of the dogs 128, 129 with the wheel 125 advances this wheel with the movement of the arm, and that in the return movement of the arm the dogs 128, 129 ride freely over the toothed periphery of the wheel 125 and permit this return movement of the arm without rotating the wheel. The engagement of the spring 149 with the adjacent upright 146 is indicated at 151.

In this case, instead of providing an over-running clutch at 14 or a locking dog at 16 as in Figure 4, brake means is provided at 155 for preventing back-lash in the feed mechanism, and particularly in the peripherally toothed wheel 125 and in the feed rolls 135 and 136. This brake means comprises a pair of thin metal plates 156, 157, which may be of spring metal and which are mounted upon a post 158 secured fast and extending laterally from the adjacent upright 146. At their free ends, the opposing faces of these plates 156, 157 are covered with leather or other suitable friction material at 160, and these friction surfaces are clamped yieldingly by screw and thumb nut means at 161 into braking engagement with the opposite faces of the gear 162, which gear 162 is mounted coaxial with the upper feed roll 135 and drives the lower feed roll from the upper feed roll but in reverse direction. A coiled spring is interposed between the plate 157 and the wing nut 161, and the nut 161 may be threaded upon or from the screw to adjust the braking engagement of the friction surfaces of the plates or shoes 156, 157 with the gear 162. As the wheel 125 is rotated or advanced with the swinging movement of the arm 126, the gear 162 is turned against the braking action of the brake means thus provided, but as the arm 126 is reset by swinging movement in the opposite direction, this brake means prevents back-lash in the gear 162 and connected feed rolls. The pinion for driving the roll 135 from the wheel 125 is indicated at 165.

While I have described certain detailed embodiments of the invention, it is to be understood that the invention is not limited to the details of these embodiments and that all possible equivalents of the details illustrated and described are contemplated within the scope of the appended claims.

I claim:

1. In a machine of the class described, the combination of a frame for rotatably journaling a roll of thin flexible wrapping material at the axis of the roll and independently of the periphery of the roll, a shear device for severing the wrapping material across its width, feed mechanism comprising a pair of feed rolls journaled on said frame and having cooperating surfaces and adapted for drawing definite increments of wrapping material from said first roll and feeding the same between said feed rolls to said shear device, said feed rolls having their axes in a plane intersecting the plane of said ma-

terial roll, with its axis in the plane in which said feed rolls are mounted and which intersects the axis of said material roll, a wheel rotatably mounted on said frame and adapted for operating 5 said feed rolls, and an arm swingable about the axis of said wheel and coacting with the wheel to turn the same upon swinging movement in one direction and swinging free of said wheel in the opposite direction, said frame extending substantially along the plane of the axis of said feed 10 rolls, said material roll and said operating wheel, whereby the stresses imposed by said feed rolls, said material roll and said operating wheel are substantially concentrically imposed upon said 15 frame.

2. In a machine of the class described, the combination of a frame for rotatably journaling a roll of thin flexible wrapping material at the axis of the roll and independently of the periphery of the roll, a shear device for severing the wrapping material across its width, feed 20 mechanism comprising a pair of feed rolls journaled on said frame and having cooperating surfaces and adapted for drawing definite increments of material directly from said first roll and feeding the same between said feed rolls to said shear device, said feed rolls having their axes in a plane intersecting the axis of said material roll, with its axis in the plane in which said 25 feed rolls are mounted and which intersects the axis of said material roll, a wheel rotatably mounted on said frame and adapted for operating said feed rolls, an arm swingable about the axis of one of said wheel and coacting with the wheel to turn the same upon swinging movement in one direction and swinging free of said wheel in the opposite direction, and means for swinging said arm alternately in opposite directions, said frame extending substantially along the plane of the axis 30 of said feed rolls, said material roll and said operating wheel, whereby the stresses imposed by said feed rolls, said material roll and said operating wheel are substantially concentrically imposed upon said frame.

45 3. In a machine of the class described, means for supporting a roll of material, feed mechanism for drawing material from the roll and feeding same through the machine, a wheel rotatably mounted and adapted for operating said feed mechanism, a swingable arm coacting with said wheel to turn same upon swinging movement in one direction, said arm swinging free of said wheel in the opposite direction, means pivotally connected to said arm for swinging the same, and means adjustably mounted on said arm swinging means for adjusting the limit to the turning movement imparted to said wheel by said swingable arm.

4. In a machine of the class described, means for supporting a roll of material, feed mechanism for drawing material from the roll and feeding same through the machine, a wheel rotatably mounted and adapted for operating said feed mechanism, a swingable arm coacting with said wheel to turn same upon swinging movement in one direction, said arm swinging free of said wheel in the opposite direction, means pivotally connected to said arm for swinging the same, said arm swinging means comprising a rod member pivotally connected to said arm, and a stop collar adjustable on said rod member for limiting swinging movement of the arm and operation of said feed means.

5. In a machine of the class described, means for supporting a roll of material, feed mecha-

nism for drawing material from the roll and feeding same through the machine, a wheel rotatably mounted and adapted for operating said feed mechanism, a swingable arm coacting with said wheel to turn same upon swinging movement in one direction, said arm swinging free of said wheel in the opposite direction, means for swinging said arm, said arm swinging means comprising a rod member pivotally connected to said arm, and means adjustably mounted on said rod member for limiting swinging movement of said arm free of said wheel.

6. In a machine of the class described, means for supporting a roll of material, a peripherally toothed wheel rotatably mounted, a swingable arm coacting with said wheel to turn same upon swinging movement in one direction and swinging free of said wheel in the opposite direction, a driving feed roll having a driving gear, a driven feed roll cooperating with said driving feed roll and having a driven gear meshing with said driving gear to drive said driven feed roll from said driving roll and in a reverse direction, a pinion for said driving roll meshing with said peripherally toothed wheel to drive the drive feed 20 roll from said wheel, and an arm swingable about the axis of the peripherally toothed wheel having dog means yieldingly coacting with opposite sides of said peripherally toothed wheel for turning said wheel upon swinging movement in one direction and permitting swinging movement of said arm in the opposite direction free of said wheel.

7. In a machine of the class described, means for supporting a roll of material, a peripherally toothed wheel rotatably mounted, a swingable arm coacting with said wheel to turn same upon swinging movement in one direction and swinging free of said wheel in the opposite direction, a driving feed roll having a driving gear, a driven feed roll cooperating with said driving feed roll and having a driven gear meshing with said driving gear to drive said driven feed roll from said driving roll and in a reverse direction, a pinion for said driving roll meshing with said peripherally toothed wheel to drive the drive feed 40 roll from said wheel, a swingable arm having dog means yieldingly coacting with said peripherally toothed wheel for turning said wheel upon swinging movement in one direction and permitting swinging movement of said arm in the opposite direction free of said wheel, a foot treadle operating mechanism, a reciprocable rod connecting said operating mechanism and said arm, and means on said rod for limiting swinging movement of said arm in the direction for turning said 50 wheel and in the opposite direction.

8. In a machine of the class described, means for supporting a roll of material, a peripherally toothed wheel rotatably mounted, a swingable arm coacting with said wheel to turn same upon swinging movement in one direction and swinging free of said wheel in the opposite direction, a driving feed roll having a driving gear, a driven feed roll cooperating with said driving feed roll and having a driven gear meshing with said driving gear to drive said driven feed roll from said driving roll and in a reverse direction, a pinion for said driving roll meshing with said peripherally toothed wheel to drive the drive feed roll from said wheel, a swingable arm having dog means yieldingly coacting with said peripherally toothed wheel for turning said wheel upon swinging movement in one direction and permitting swinging movement of said arm in the opposite direction free of said wheel, a reciprocable rod connected to 70

said arm for swinging the same in the direction for turning said wheel, a reciprocable rod connected to the opposite end of said arm, and spring means associated with said second rod for resetting said arm by turning movement free of said wheel.

9. In a machine of the class described, means for supporting a roll of material, feed mechanism for drawing material from the roll and feeding same through the machine, a wheel rotatably mounted and adapted for operating said feed mechanism, a swingable arm coacting with said wheel to turn same upon swinging movement in one direction, said arm swinging free of said wheel in the opposite direction, a part having a generally horizontal surface over which the sheet is fed from the machine, guide means spaced substantially equal to the width of the material and cooperating with opposite edges of the material to guide the same over said surface, said guide means comprising a guide member adjustably mounted adjacent one edge of the material upon the part with the generally horizontal surface for adjustment in a direction across the width of the material, a cutting member at the outer end of said surface, and a knife pivoted at one end and adjacent said guide means swingable into cooperation with said cutting member to sever the material transversely across its width.

10. In a machine of the class described, means for supporting a roll of material, feed mechanism for drawing material from the roll and feeding same through the machine, a wheel rotatably mounted and adapted for operating said feed mechanism, a swingable arm coacting with said wheel to turn same upon swinging movement in one direction, said arm swinging free of said wheel in the opposite direction, a part having a generally horizontal surface over which the sheet is fed from the machine, guide means spaced substantially equal to the width of the material for guiding same over said surface, a cutting member at the outer end of said surface, a knife swingable into cooperation with said cutting member to sever the material transversely across its width, and means for mounting said knife pivotally and yieldingly at one end, said knife being normally disposed slightly obliquely with respect to said cutting member and moving into parallel relation to said member upon cooperation therewith.

11. In combination, a horizontal top, uprights mounted thereon and having means for journaling rotatably a roll of material, a peripherally toothed wheel rotatably mounted on one of said uprights, a feed roll geared to said wheel, a second feed roll geared to said first feed roll to be driven in reverse direction thereby, an arm swingable on the axis of said peripherally toothed wheel, and means on said arm and yieldingly engaging the teeth in said wheel for turning said wheel by swinging movement of the arm in one direction and permitting swinging movement of the arm free of the wheel in the opposite direction.

12. In combination, a horizontal top, uprights mounted thereon and having means for journaling rotatably a roll of material, a peripherally toothed wheel rotatably mounted on one of said uprights, a feed roll geared to said wheel, a second feed roll geared to said first feed roll to be driven in reverse direction thereby, an arm swingable on the axis of said peripherally toothed wheel, means on said arm and yieldingly engaging the

teeth in said wheel for turning said wheel by swinging movement of the arm in one direction and permitting swinging movement of the arm free of the wheel in the opposite direction, a foot treadle beneath the top, connecting means between said foot treadle and one end of said arm and operating reciprocably through an opening in said top, means connected to the opposite end of said arm and operating reciprocably through another opening in said top, an abutment on said last means, and a spring confined between said abutment and said top for resetting said arm.

13. In a machine of the class described, a pair of upright frame members, a material roll having journals at its opposite ends for rotatable mounting in said frame members, an abutment on one journal, and a spring arm fixedly anchored and cooperating yieldingly with the opposite end of said material roll to force said roll endwise into cooperation with the upright frame member at the other end of the roll.

14. In a machine of the class described, a pair of upright frame members, a material roll having journals at its opposite ends for rotatable mounting in said frame members, an abutment on one journal, a spring arm fixedly anchored and cooperating yieldingly with the opposite end of said material roll to force said roll endwise into cooperation with the upright frame member at the other end of the roll, and means for adjusting said spring arm toward and away from the upright frame member cooperating with one end of the material roll to accommodate rolls of different lengths.

15. In a machine of the class described, a frame for supporting a roll of material, feed mechanism for drawing material from the roll and feeding same through the machine, a wheel rotatably mounted and adapted for operating said feed mechanism, a swingable arm coacting with said wheel to turn same upon swinging movement in one direction and swinging free of said wheel in the opposite direction, said feed mechanism comprising feed rolls having meshing gears, brake means for yieldingly preventing back-lash in said feed means, said brake means comprising a pair of brake arms secured to the frame and embracing and cooperable laterally with opposite sides of one of the meshing gears of said feed rolls, and means yieldingly clamping the brake arms into braking engagement with the opposite faces of said gear.

16. In a machine of the class described, means for supporting a roll of material, feed mechanism for drawing material from the roll and feeding same through the machine, a wheel rotatably mounted and adapted for operating said feed mechanism, a swingable arm coacting with said wheel to turn same upon swinging movement in one direction and swinging free of said arm in the opposite direction, said feed mechanism comprising feed rolls having meshing gears, and brake means cooperating with one of said gears to yieldingly prevent back-lash in said feed means, said brake means comprising a pair of spring arms adapted to receive one of said last gear members between same and having friction surfaces pressed yieldingly into engagement with opposite sides of said gear member.

17. In a machine of the class described, means for supporting a roll of material, feed mechanism for drawing material from the roll and feeding same through the machine, a wheel rotatably mounted and adapted for operating said feed

- mechanism, a swingable arm coacting with said wheel to turn same upon swinging movement in one direction, said arm swinging free of said wheel in the opposite direction, treadle means, 5 a connecting link between said treadle means and said arm for swinging the arm by said treadle means, and means adjustably mounted on said connecting link for limiting the turning movement imparted to said wheel by said arm.
- 10 18. In a machine of the class described, means for supporting a roll of material, feed mechanism for drawing material from the roll and feeding same through the machine, a wheel rotatably mounted and adapted for operating said feed
- mechanism, a swingable arm coacting with said wheel to turn same upon swinging movement in one direction, said arm swinging free of said wheel in the opposite direction, treadle means, 5 a connecting link between said treadle means and said arm for swinging the arm in the direction in which said wheel is turned by said arm, spring means for swinging said arm free of said wheel in the opposite direction, and means adjustably mounted on said connecting link for 10 limiting the turning movement imparted to said wheel by said arm.

HARRY S. RUBENS.

CERTIFICATE OF CORRECTION.

Patent No. 1,996,306.

April 2, 1935.

HARRY S. RUBENS.

It is hereby certified that error appears in the printed specification of the above numbered patent requiring correction as follows: Page 5, first column, lines 1, 2 and 3, claim 15, and lines 29, 30 and 31, claim 2, strike out the words "with its axis in the plane in which said feed rolls are mounted and which intersects the axis of said material roll" and insert the same after "frame" in lines 4 and 32, of said claims; and lines 3 and 31, claims 1 and 2, strike out the comma, before the article "a"; and that the said Letters Patent should be read with these corrections therein that the same may conform to the record of the case in the Patent Office.

Signed and sealed this 28th day of May, A. D. 1935.

Leslie Frazer
